UNITED STATES PATENT OFFICE.

MARVIN EVANS, OF PHARR, TEXAS.

DREDGE.

1,398,131.

Specification of Letters Patent. Patented Nov. 22, 1921.

Application filed June 15, 1920. Serial No. 389,174.

To all whom it may concern:

Be it known that I, MARVIN EVANS, citizen of the United States of America, residing at Pharr, in the county of Hidalgo and State 5 of Texas, have invented new and useful Improvements in Dredges, of which the following is a specification.

This invention relates to excavating machines particularly designed for canal digging and is an improvement upon a patent 10 granted to Charles S. Butterfield, March 13, 1917 and numbered 1,219,371.

An object of the present invention is to provide means for supporting the excavating 15 machine upon a frame suspended from either side of the excavation, to permit of the position of the machine being readily changed as the work progresses.

Another object is the provision of means 20 for supporting the machine in a firm and stable manner, so that the maximum of power may be applied to the excavating buckets, while the supporting means will be maintained in proper position or elongated 25 for the convenient travel of the machine.

Another object is the provision of a carriage which is movable over supporting 30 tracks and over which the machine proper may be moved, so as to provide for a movement of the machine independent of the carriage.

Other objects and advantages of the invention will appear as the following description is read in connection with the accompanying 35 drawings, the invention consisting of the details of construction, combination and arrangement of parts which will be hereinafter fully described.

In the drawings:—

40 Figure 1 is an elevation of a dredging machine embodying the present invention.

Fig. 2 is an elevation at right angles to Fig. 1.

Fig. 3 is a plan view of the carriage.

45 Fig. 4 is a similar view of the rail supporting stringers with the rails mounted thereon, Fig. 5 is a section on the line 5—5 of Fig. 4.

Referring to the drawings in detail, where- 50 in like characters of reference denote corre- sponding parts, the machine proper which is illustrated and described in the afore-men- tioned Butterfield patent is herein shown as comprising a platform 10 of suitable con- struction, having extending upwardly there- 55 from a derrick which includes inclined side

bars 11 and cross bars 12. The lower ends of the side bars are pivoted to the platform as shown at 13, while the derrick is support- ed at the outer inclination by means of cables 60 14 as illustrated in Fig. 2.

Pivottally mounted upon opposite sides of the platform 10 are booms 15, which carry sheaves or pulleys 16, at their outer ends. Traveling from these sheaves or pulleys are 65 out hauled drag lines 17, having one end attached to the excavating buckets 18 and their opposite ends connected to suitably hoisting apparatus, such as shown in the afore-mentioned patent. The buckets 18 also 70 have connected back drag or non-haul cables 19, which pass through pulleys or sheaves 20 suspended from the top of the derrick and have their ends also connected to suitable hoisting mechanism. The booms 15 are 75 regulated through the medium of an elevat- ing cable 21, one end of which is secured to the outer end of a boom, the said cable passing from a pulley or sheave 22 and having its fall line secured to a cleat 23 carried by 80 the derrick.

The foregoing structure is substantially of the same as that shown and described in the Butterfield patent, the present invention consisting of the means for mounting this 85 structure. For this purpose there is pro- vided a carriage which is designated in its entirety by the reference character 24. It is made up of longitudinally extending I beams 25, which are connected by trans- 90 verse channel beams 26 extending across the top of the I beams. Depending from the I beams 25 are spaced pairs of transversely extending I beams 27, while journaled in these last mentioned I beams upon axles 95 28 are flanged wheels 29. The wheels 29 have appreciably wide treads so as to ride over spaced pairs of rails 30 as illustrated in Fig. 1. In addition the I beams 25 have mounted thereon beams 32, which carry 100 flanged wheels or rails 33 for engagement with I beams 34, depending from and se- cured to the beam platform 10.

In this arrangement the machine proper 105 may be moved upon the carriage independ- ently thereof to position the said machine in the proper position for use, while the carriage and machine may be moved over the tracks 30 when it is desired to move it any appreciable distance.

110 As shown in Fig. 1 the machine is de- signed to be supported across the top of an

excavation and for this purpose the rails 30 are laid along the edge of the excavation and in order to hold these rails in proper position and provide a proper length of 5 trackage for the movement of the machine, the said rails are secured upon stringers 35. These stringers are arranged in sections 36, as shown in Fig. 4, one rail of each section overlapping the end of the adjacent section 10 to provide brake joints in the rails. Secured transversely of the bottom of the stringer sections 36 are cleats 37 which act to anchor the stringers and prevent the tracks from turning and buckling. This 15 provides an exceedingly simple and convenient means for accomplishing the purpose.

The invention is susceptible of various changes in its form, proportions and minor details of construction, and the right is hereby 20 reserved to make such changes as properly fall within the scope of the appended claims.

Having described the invention what is claimed is:—

25 1. An excavating machine embodying a

platform, excavating mechanism supported thereby, tracks located upon each side of the excavation, a wheel supported carriage movable over the tracks, said carriage comprising a frame and including longitudinal 30 beams and transverse beams, wheels journaled transversely of each end of the carriage for supporting the same, wheels journaled upon the top of said carriage and tracks located beneath the bottom of the 35 platform and operating over the last mentioned wheels to provide independent relative movement of the platform and carriage.

2. An excavating machine embodying a platform, excavating mechanism supported thereby, a track supported carriage located beneath the platform, spaced parallel beams supported upon the carriage and rollers journaled upon said beams for supporting the platform upon the carriage to permit 40 45 of relative independent movement.

In testimony whereof I affix my signature.

MARVIN EVANS.
